UNITED STATES PATENT OFFICE.

CHARLES F. GRAHL, OF PHILADELPHIA, PA., ASSIGNOR TO THE FAIR HILL MANUFACTURING COMPANY, OF SAME PLACE.

DESIGN FOR CHENILLE-CORD.

SPECIFICATION forming part of Design No. 15,113, dated July 1, 1884.

Application filed November 30, 1883. Term of patent 7 years.

To all whom it may concern:

Be it known that I, CHARLES FLORENCE GRAHL, of Philadelphia, in the county of Philadelphia, and in the State of Pennsylvania, have 5 invented a certain new and useful Design for Chenille-Cord for Upholstery, Millinery, &c.; and I do hereby declare that the following is a full, clear, and exact description thereof, reference being had to the accompanying 10 drawing, in which is shown my new design.

My invention consists of a chenille-cord, A, having spiral bands a of plain pile alternating with spiral bands a' of loops. These bands I make, as shown, of equal widths, and

the shape of the cord is not round but flattened.

Having thus set forth the nature of my design, what I claim as new is—

A design for chenille-cord, consisting of alternate spiral bands of plain pile and loops, 20 as described and shown.

In testimony that I claim the foregoing I have hereunto set my hand this 24th day of November, A. D. 1883.

CHARLES F. GRAHL.
